RAIL BRACE

George Arnold, Shaker Heights, Ohio, assignor to
 Cleveland Frog & Crossing Co., Cleveland, Ohio,
 a corporation of Ohio

Application November 25, 1939, Serial No. 306,124

4 Claims. (Cl. 238—292)

This invention relates to rail braces for holding railway rails against lateral movement.

An object of the invention is to provide a rail brace which is efficient, which possesses the required adjustments relative to the rail, which is so formed as to have accurate bearing contact against the rail at the critical points and which is composed of a minimum number of parts and is therefore economical to manufacture and install.

Another object is to provide a rail brace including a wedge member for moving the brace tightly against the rail and wherein a single set of fastening means is employed to hold the brace block in position on the base plate and in tight engagement with the wedge member.

A further object is to provide a rail brace including a wedge member for moving the brace tightly against the rail and wherein means is provided for positively holding the wedge against longitudinal movement when it has been assembled in operative position.

A still further object is to provide a rail brace including a wedge member for moving the brace tightly against the rail and wherein the brace block and the wedge member are provided with cooperating teeth or serrations adapted to interlock when the wedge member has been properly positioned with respect to the block and the latter secured to the base plate, together with means for positively locking the wedge member against longitudinal movement relative to the brace block and effective only when said cooperating teeth or serrations are fully interengaged.

A still further object is to provide a rail brace wherein the brace block has an internal overhanging extension, heel or lip beneath which the wedge is located, thus reducing to a minimum the number of parts required for clamping the wedge in operative position.

Further and additional objects and advantages not hereinbefore referred to will become apparent hereinafter during the following detailed description of the preferred embodiment of the invention that is illustrated in the accompanying drawings. Referring to the drawings,

Fig. 1 is a fragmentary top plan view of a railway rail and base plate with the rail brace of the invention mounted on the base plate and engaging the side of the rail, a certain portion of the rail head being broken away and shown in section.

Fig. 2 is a side elevational view of the base plate and an end elevational view of the rail

brace, the rail being shown in transverse vertical section.

Fig. 3 is a fragmentary vertical sectional view of the rail, base plate and rail brace taken substantially on the irregular line 3—3 of Fig. 1 looking in the direction of the arrows.

Fig. 4 is a side elevational view of the base plate, the rail brace and a portion of the rail and is taken looking from the right hand side of Fig. 2.

Fig. 4a is a fragmentary end elevational view of a portion of the brace block.

Fig. 5 is a perspective detail view of the wedge member.

Fig. 6 is an end elevational view of the die members used in sizing, shaping, smoothing and ironing the brace blocks of the rail braces after annealing, a brace block being shown in position therein.

Fig. 7 is a vertical longitudinal sectional view through the die members and brace block shown in Fig. 6 and is taken substantially on line 7—7 of Fig. 6 looking in the direction of the arrows.

Fig. 8 is a perspective view of the die used in sizing, shaping, smoothing and ironing the wedge members after annealing.

Fig. 9 is a longitudinal vertical sectional view through the die member of Fig. 8 and is taken substantially on line 9—9 of Fig. 8 looking in the direction of the arrows, a wedge member being indicated in position in the die cavity by dot and dash lines, and

Fig. 10 is a vertical longitudinal sectional view through the die member of Fig. 8 and is taken substantially on line 10—10 of Fig. 8 looking in the direction of the arrows, the wedge member being shown in position in the die cavity by dot and dash lines.

Referring to Figs. 1 to 5 inclusive of the drawings, it will be seen that the base plate 11 extends beneath the rail 12 and can be secured to the ties or other suitable supporting members (not shown) as is well understood in the art.

The upper side of the base plate 11 is provided with a recess in which the base flanges of the rail 12 are located as well as the rail brace later to be described. The outer edge of the left hand base flange of the rail (as viewed in the drawings) abuts against the side 13 of the recess in the base plate 11, whereby the rail is held against movement toward the left relative to the base plate 11. A straight sided stop block or strip 14 is secured in the recess by rivets or other suitable securing means and abuts the other side 15 of the recess in said base plate.

The rail brace comprises a brace block indicated in general by the numeral 16 and preferably formed from a casting which has been annealed and then sized and shaped by die operations as will later be described and which has at the upper end of a vertically extending portion 17 a curved bearing surface 18 which suitably interfits the underside of the rail head and a portion of the vertical web of the rail adjacent the head and which extends longitudinally of the rail the full length of the brace block. The brace block 16 has a substantially horizontal portion 19 merging into the vertical portion 17 and shaped on its underside adjacent said vertical portion to form, together with the lower inner surface of the vertical portion, a curved bearing surface 20 that accurately interfits and engages the merging curved outer surface of the rail web and the curved upper surface of the right hand (as viewed in the drawings) base flange of the rail 12.

Each end of the brace block 16 is provided with upstanding flanges 21 interconnecting the vertical portions 17 and the horizontal portion 19 and said flanges are also shaped to have bearing surfaces 22 forming a continuation of the bearing surface 20 and interfitting with the merging curved surfaces of the rail web and the right hand rail flange as viewed in the drawings.

The portion 19 of the brace block is provided on its underside with downwardly projecting spaced ribs, one of which is indicated at 23 and extends transversely and diagonally of the base plate 11. The horizontal portion 19 of the brace block is extended beyond the rib 23 and such extension of the portion 19 provides an overhanging lip or wedge engaging part 24 extending substantially to the stop block or strip 14. The underside of the lip or wedge engaging part 24 is provided with a series of serrations or teeth 25 transversely disposed with respect to the lip and extending substantially throughout the longitudinal length thereof.

The horizontal portion 19 of the brace block is provided intermediate the flanges 21 with a pair 45 of slots 26 elongated in a direction longitudinally of the base plate 11 and bolts 27 carried by the base plate 11 extend through said slots and hold the brace block against movement transversely of the base plate, while permitting movement or 50 adjustment of the brace block toward the rails 12 to bring the bearing surfaces 18, 20 and 22 into tight interfitting engagement with the cooperating portions of the rail. A washer plate 28 is provided with a pair of spaced openings through 55 which the bolts 27 extend, while suitable lock-washers 29 and cap nuts 30 are mounted on the threaded upper ends of the bolts 27 and above the plate 28, from which it will be seen that the brace block can be clamped in adjusted position 60 upon the base plate 11. The cap nuts 30 protect the threads of the bolts 27 from exposure to weather or from brine dripping from refrigerator cars or otherwise falling thereon, thus lessening the rusting and deterioration of the bolt threads.

65 A wedge member or bar 31 is arranged in the tapered space between the converging right hand side of the rib 23 of the brace block and the left hand side of the stop block or strip 14 and beneath the lip or wedge engaging part 24 with the 70 straight side of the wedge engaging the straight side of the wedge engaging the straight side of the stop block 14, while the inclined side of the wedge engages the diagonal rib 23.

The upper side of the wedge 31 is provided 75 with a series of transversely disposed serrations

or teeth 32 that extend substantially throughout the longitudinal length of the wedge and which are adapted to interlock with the serrations or teeth 25 on the underside of the lip or wedge engaging part 24 of the brace block, wherefore the wedge will be held against movement transversely of the base plate 11.

In order to insure that the teeth or serrations 25 and 32 are properly engaged and to positively hold the wedge against undesired longitudinal movement, relative to the brace block once the wedge is in assembled position, the following construction is employed:

The horizontal portion 19 of the brace block and beyond the uppermost flange 21 as viewed in Fig. 1, or the right hand flange 21 as viewed in Fig. 4, is provided with an integral outwardly extending lug 33 and which lug has formed therein a pair of openings 34 and 35 extending through the lug and spaced vertically thereof. The wedge 20 31 on its straight side is provided with a series of longitudinally spaced transversely extending openings 36 located above a similar series of transversely extending openings 37. The series of openings 36 and 37 are spaced vertically of 25 each other a distance corresponding to the vertical spacing of the openings 34 and 35 in the lug 33, while the openings 36 are staggered with respect to the openings 37 in a direction longitudinally of the wedge, with the horizontal distance between the centers of the openings 36 and 37 corresponding to the pitch of the teeth or serrations 25 and 32.

In installing the rail brace the brace block 16 is positioned upon the base plate 11 with the 35 bolts 27 extending through the openings 26 and with the bearing and engaging surfaces 18, 20 and 22 of the brace block in approximate engagement with the cooperating surfaces of the rail web and rail flange.

The wedge 31 is inserted beneath the lip 24 and between the rib 23 and stop block 14 as far as it will readily go, after which the plate washer 28 is positioned upon the bolts 27 as are also the lock spring washers 29. The cap nuts 30 are screwed down upon the bolts but only tight enough to obtain a certain degree of spring tension on the bolts because of the spring washers 29. The wedge 31 can then be driven inwardly to force the block tightly against the rail 12.

It will be seen that due to the fact the nuts have been screwed down until the bolts are under spring tension the teeth or serrations 25 and 32 on the block and wedge will ride over each other as the wedge is driven inwardly, since the block 55 because of the spring action of the washers will give sufficiently for this purpose.

Also, since the nuts have been tightened down to the extent just stated and since the block has an extensive engagement with the flange of the 60 rail the wedge cannot be driven so hard or the block forced so tightly against the rail as to tip the latter and raise it off its seat on the base plate.

In driving the wedge inwardly to force the 65 block tightly against the rail care should be taken that the teeth or serrations of the block and wedge are fully engaged and this can be audibly determined since the spring tension placed on the bolts by the spring washers 29 causes the teeth 70 or serrations to come into intermeshing engagement with a snapping action.

When the brace block has been thus tightly forced against the rail 12 the nuts 30 are screwed down upon the bolts 27, with the result that the 75

brace block is held tightly against the rail with the bearing surfaces 18, 20 and 22 of the block in tight accurate interfitting relationship with the cooperating surfaces of the rail.

- 5 The brace block then acts to exert a sidewise pressure against the rail, as well as a downward pressure thereon to hold the rail tightly against the side 13 of the recess in the upper side of the base plate 11 and flat on said base plate.
- 10 It will also be seen that when the nuts 30 are screwed down tightly on the bolts 27 the teeth or serrations 25 on the underside of the lip 24 of the brace block interlock with the teeth 32 on the upper side of the wedge 31, wherefore the wedge 15 is held against movement transversely of the base plate 11.

In addition to the audible clicking of the teeth or serrations 25 and 32 into intermeshing engagement with each other during the operative 20 assembly of the rail brace, the rail brace is provided with a further and more definite means for determining when the teeth or serrations are completely intermeshed. The openings 36 and 37 in the wedge 31 will only align respectively with the openings 34 and 35 in the lug 33 when the teeth or serrations 25 and 32 are fully intermeshed, and hence the operator can determine when this condition is present by inserting a cotter pin 38 through the opening 34 and an opening 30 36 aligned therewith or through the opening 35 and an opening 37 which is in alignment therewith. If neither of the openings 34 and 35 are in alignment with one of the openings 36 or 37, respectively, the operator definitely knows that 35 the wedge is not correctly positioned and that the teeth or serrations 25 and 32 are not fully intermeshed, it being remembered that the openings 36 and 37 are displaced in a direction longitudinally of the rail a distance corresponding to the 40 pitch of said teeth or serrations, and hence the openings 34 or 35 will be aligned, respectively, with one of the openings 36 or 37 only when the teeth or serrations are fully intermeshed.

In addition to the advantageous function just 45 set forth said openings 34 and 35 and the openings 36 and 37, together with the cotter pin 38, provide for a positive lock against longitudinal movement of the wedge relative to the brace block while permitting proper adjustment of the wedge and brace block with complete and full intermeshing of the teeth or serrations 25 and 32.

It will be seen that the rail brace embodying the present invention requires only one set of 55 fastening or securing means to clamp the brace block tightly against the rail and against the wedge.

The use of only one set of fastening or securing means for the dual purpose just referred to 60 simplifies the structure of the rail brace, reduces the number of its parts to a minimum and facilitates the application or assembly of the rail brace in operative position with respect to the rail.

65 Heretofore it has been necessary to provide separately applied means for holding the brace block tightly against the rail and against a wedging member, thus increasing the number of parts and the cost of the rail brace, as well as the 70 time required to apply the brace to the rail.

In addition, a rail brace constructed in accordance with the present invention is compactly formed and is so shaped and dimensioned as to reduce to a minimum any tendency of the rail brace to rock under the lateral pressure of the 75

rail thereagainst, wherefore the bolts and nuts constituting the securing means are subjected to minimum strains or shearing stresses.

It will also be noted that notwithstanding the elimination of parts separate from the brace 5 block for holding the wedge and the use of an overhanging lip or wedge engaging part that is integral with the brace block, the securing bolts 27 are located relatively close to the rail 12 thus eliminating undesirable and excessive leverages 10 which multiply the rocking forces to which the rail brace and rail are subjected.

As previously set forth, it is most essential if a rail brace is to function efficiently that said brace be accurately sized or dimensioned and 15 that the portions thereof which engage the rail correctly interfit with the rail and have full and correct bearing engagement therewith.

It has been customary heretofore to form the rail braces of castings, with the result that said 20 braces are brittle and the critical portions thereof do not accurately interfit and have definite and correct bearing engagement with the co-operating surfaces of the rail.

It is proposed to manufacture rail braces such 25 as have been described in detail herein in such way that the braces will not be brittle and will be accurately sized or dimensioned and with those portions of the braces that interfit the rail formed with the correct and necessary configurations 30 so as to have full, accurate and definite bearing engagement with the cooperating surfaces of the rail.

In carrying out this method the rail braces including the wedges are first formed by the 35 usual casting operations to the required size and in such way that the teeth or serrations 25 and 32 are formed in the brace block and the wedge.

The cast brace blocks and wedges are then 40 annealed to render the metal malleable and to obviate the objection of brittleness therein. The high temperatures to which the brace blocks and wedges are subjected in the course of the annealing operation tend to distort the block and wedges so as to vary the dimensions thereof and 45 change their configuration and especially the critical portions of the braces which engage with the rail and render such portions rough as well as distorting the serrations or teeth 25 and 32 to an extent that would either fully or 50 partially prevent their proper intermeshing or interengagement.

It is proposed to subject the brace blocks and wedges after annealing to render the same malleable to simple and expeditious operations serving to accurately size or dimension the blocks and wedges; smooth, shape, compact, compress or iron down the bearing surfaces thereof such as the surfaces 18, 20 and 22 and also to correct any malformations which may have occurred in the teeth or serrations 25 and 32. 60

In Fig. 6 a cast and annealed malleable brace block 16 is shown in position in a die member 39 that is provided with die cavity shaped complementary to the configuration of the underside of the rail head, the outer side of the rail web and the upper side of the rail flange, so that the bearing surfaces 18, 20 and 22 of the brace block will substantially engage with the portions of the surface of the cavity corresponding 65 to the enumerated portions of the rail.

It will be noted that a removable die block 40 is positioned in the cavity of the die member 39 and that this block is engaged by the bearing surface 18 and corresponds in size and shape to 70 75

the underside of the rail head and the rail web that is engaged by the bearing surface 18. It will be understood that removable die blocks 40 made in accordance with the size of the particular rails to which the rail brace is to be applied will be mounted in the die member 39 as desired.

When the annealed casting 16 has been positioned as shown in Fig. 6 a pressure applying member or ironer 41 is moved into engagement with the casting by suitable pressure applying means such as a hydraulic press and said member 41 is provided with a reduced lower end 42 that extends between the flanges 21 of the brace block and is shaped to interfit the vertical portion 17 and the horizontal portion 19 thereof. It will also be noted that the member 41 is provided with curved shoulders 43 which engage the outer surfaces of the flanges 21 of the brace block.

When the annealed casting in the form of the brace block 16 is subjected to the tremendous pressure applied thereagainst by the member 41 distortion which may have occurred in the brace block in the annealing operation is removed, the brace block is accurately sized and the bearing surfaces 18, 22 and 20 are ironed or compacted into the correct configuration having the requisite smoothness and hardness to accurately interfit the complementary surfaces of the rail so as to enable the rail brace to be properly positioned relative to the rail to effectively perform its function.

Subjecting the brace block to the pressures of the die members, as already stated, removes distortion therefrom, correctly shapes and sizes the brace block, while the bearing surfaces 18, 20 and 22 are not only accurately shaped but are subjected to what may be termed a burnishing or ironing operation that smooths such surfaces and compacts the metal. When the brace block has been thus treated the material thereof will be malleable and the block will be correctly formed to function efficiently when applied to a rail.

The annealed wedges 31 are subjected to similar operations by means of a die member 44 which is provided with a cavity 45 shaped to receive the wedge when positioned therein with its broad dimension horizontal. The wedge 31 is shown in position in the cavity 45 by dot and dash lines in Fig. 9 and it will be noted that the side of the wedge upon which the teeth or serrations 32 are formed is arranged downwardly with the plain ends of the wedge at each end of the series of teeth or serrations engaging raised portions 46 and 47 formed in the bottom of the cavity, while the teeth or serrations are located intermediate said raised portions in a recess 48.

The wedge 31 is properly positioned in the cavity 45 by means of the shoulders between the raised portions 46 and 47 and the recess 48 and by a pin 49 which engages with the small flat end of the wedge. When the wedge has been positioned in the cavity 45 it is subjected to the pressure of a member not shown and preferably forming part of a hydraulic press, with the result that the wedge if any of its under and broad side projects above the cavity 45 is compacted into the cavity 45 and thus accurately sized insofar as its thickness is concerned, while distortion in the wedge and in the teeth or serrations 32 is reduced.

The wedge is then positioned in a cavity 50 preferably formed in the same die member 44 in order to be sized with respect to its dimensions

in another direction, i. e., its width. The cavity 50 has its bottom wall inclined, as indicated at 51, to correspond to the inclined side of the wedge and said wedge is mounted in the cavity 50 with its inclined side in engagement with the bottom wall 51 of the cavity, while the large end of the wedge engages a plate 52 secured to the member 44 and the small end of the wedge engages a pin 53 projecting upwardly from the bottom wall 51 of the cavity. If the wedge 31 is of excessive width the straight side of the wedge will extend above the cavity and consequently when the pressure applying member is brought into operative position it will engage the straight side of the wedge and compact the wedge fully into the cavity, thus properly sizing the wedge with respect to its width, truing the sides thereof and removing distortion therefrom.

It will be understood that two wedges may be operated on simultaneously in the die member, with one wedge in the cavity 45 and one in the cavity 50, and which latter wedge has previously been sized and pressed in the cavity 45.

It will have been seen that by virtue of utilizing the die pressing operations described rail braces can be produced which are accurate in size and shape and which although made from castings and then annealed to remove the brittleness of the material and render the same malleable have the distortions and inaccuracies which might be caused by the heat of the annealing operations removed therefrom and the members brought to the proper size, dimension and smoothness.

Although the invention has been described herein with reference to a particular structure it will be understood that the invention is not to be limited thereto but may have other forms and adaptations within the scope of the appended claims.

Having thus described my invention I claim:

1. A rail brace adapted to be used with a base plate arranged beneath a railroad rail and comprising a brace block having portions for engaging and accurately interfitting portions of the rail and mounted for adjustment toward the rail, means for clamping said brace block against the rail and for holding the block against movement transversely of the base plate, and a wedge member for forcing said block tightly against the rail, said block and said wedge member being provided with cooperating teeth or serrations which are adapted to be brought into interlocking relationship when said means locks the block in position against the rail, said block and said wedge member also being provided with cooperating openings aligning with each other only when said teeth or serrations are fully interlocked and thus signifying such condition and enabling a positive locking element to be passed through said openings.

2. A rail brace comprising a base plate to be arranged beneath a railway rail, a brace block on said plate and having portions for engaging and accurately interfitting with portions of the rail, said brace block being provided with an elongated slot and said base plate being provided with a bolt extending through said slot and carrying means for clamping the block in adjusted position, said slot and said bolt enabling said block to be adjusted toward the rail while holding the block against movement transversely of the plate, and a wedge member for forcing said block tightly against the rail and provided on its upper surface with teeth, said block being provided with an integral lip overhanging said wedge member and

- having on its underside teeth cooperating with the teeth on the wedge member whereby when said block is clamped in position against the rail said teeth will interengage, said block and said wedge being provided with cooperating openings aligning with each other only when said teeth are interengaged to thus signify such condition and to enable a positive locking member to be passed through said openings.

3. A rail brace comprising a base plate to be arranged beneath a railway rail, a brace block mounted on said plate and having portions providing accurately formed bearing surfaces complementary to portions of the rail and adapted to engage the latter, said block and said plate having cooperating means whereby said block can be adjusted toward the rail and locked in adjusted position, said block at its edge remote from the rail being provided with an integral overhanging lip having teeth on its underside, said block also being provided on its underside adjacent said overhanging lip with a downwardly projecting rib extending transversely and diagonally of the base plate, and a wedge member arranged beneath said overhanging lip and cooperating with said rib and a portion of said base plate for forcing the bearing surfaces of said block tightly against the rail, said wedge member being provided on its upper surface with teeth which interlock with the teeth on the underside of the overhanging lip when said block is clamped in adjusted position by said cooperating means, said block and said wedge member also being provided with openings aligning with each other only when said teeth are fully interlocked, thus signifying such condition and permitting the insertion of a positive locking element through said openings.

4. A rail brace comprising a base plate to be arranged beneath a railway rail, a brace block mounted on said plate and having portions thereof formed to provide bearing surfaces complementary to portions of the rail, a wedge member for forcing said block tightly against the rail, means for locking said block in position against the rail and for holding said block against movement transversely of the base plate, said block and said wedge member being provided with integral cooperating teeth which are brought into interlocking relationship when said means locks the block in position against the rail, said block also having a portion provided with a pair of vertically spaced openings and said wedge member being provided with a pair of vertically spaced series of transversely extending openings, the openings of one series being staggered with respect to the openings of the other series a distance corresponding to the pitch of said cooperating teeth, whereby an opening of one or the other of said series of openings in the wedge member will align with one or the other of the vertically spaced openings in the brace block only when said teeth are fully interlocked.

GEORGE ARNOLD.

GEORGE ARNOLD.
